UNITED STATES PATENT OFFICE.

CHARLES TURNEY HIXSON, OF RINGWOOD, OKLAHOMA TERRITORY.

TRACTION-ENGINE TENDER.

No. 810,145.

Specification of Letters Patent.

Patented Jan. 16, 1906.

Application filed June 24, 1905. Serial No. 266,797.

To all whom it may concern:

Be it known that I, CHARLES TURNEY HIXSON, a citizen of the United States, residing at Ringwood, in the county of Woods and 5 Territory of Oklahoma, have invented a new and useful Traction-Engine Tender, of which the following is a specification.

This invention relates to means for transporting the supplies of fuel and water to a 10 traction-engine.

One of the principal objects is to provide novel means for maintaining proper alinement between an engine and its tender without regard to the direction of movement and 15 without transmitting any portion of the tender-load to the engine, said means permitting the necessary relative movement of the engine and tender when passing over uneven surfaces and the like.

Another object is to provide a roof or awning for the tender and to arrange the same and the means for connecting the tender to 20 the engine so that said roof or awning will always constitute a proper protection or cab 25 for the engineer.

The preferred embodiment of the invention is illustrated in the accompanying drawings, wherein—

Figure 1 is a side elevation showing the 30 novel tender connected to a traction-engine. Fig. 2 is a skeleton view in plan, showing the connections between the tender and engine. Fig. 3 is a perspective view of the tender with the reservoir and roof removed. Fig. 4 is a 35 horizontal sectional view through the front portion of the tender. Fig. 5 is a vertical longitudinal sectional view through the rear portion of said tender.

Similar reference-numerals designate cor- 40 responding parts in all the figures of the drawings.

In the embodiment illustrated a well-known type of traction-engine is shown and is designated by the reference-numeral 6, 45 said traction-engine having a pivoted front axle 7, constituting a part of the steering-gear, said axle having connected thereto chains or cables 8, which are oppositely wound on a drum 9. The drum is actuated 50 by means of the usual hand-shaft 10, having a worm connection 11 at one end with the drum and provided at its other end with a suitable hand-wheel 12. These parts are well known to the art and may be varied as desired, the same being illustrated merely for

the purpose of showing the connections between the tender and the engine.

The tender includes a running-gear that comprises a reach-bar 13, carrying at its front end a transverse bolster 14 and at its rear end another bolster 15, the latter being associated with a suitable coupler 16. Braces 17, connected to the end portions of the front bolster 14, have their rear ends fastened, as shown at 18, to the reach-bar between the 60 ends thereof. The front ends of these braces are extended and form eyes 19, located in advance of the reach-bar 14. Links 20, spaced apart, have bifurcated rear ends 21, that receive the eyes 19, bolts 22, passing through the ends and eyes, constituting pivotal connections between the same. Crossed braces 23 connect the opposite ends of the links. Pivoted to the front ends of said links are 65 ears 24, which ears are arranged to be secured to the engine.

Front and rear axles 25 and 26 are respectively pivoted to the front and rear ends of the reach-bar 13. These connections preferably comprise ball-and-socket members 27, 70 one of said members comprising sections secured to the axle and having a socket therein, the other being provided with a ball that fits within the socket and is secured to the under side of the reach-bar.

Braces 28 have 75 pivotal connections with the axles in line with the pivot-axes thereof, said braces being fastened, as shown at 29, to an intermediate portion of the reach-bar. Cables 30, preferably, though not necessarily, chains, 80 have secured to their rear ends stirrups 31, which are adjustably fastened to a flange-plate 32, secured to the rear axle 26, said stirrups being located on opposite sides of the pivot-axis of the axle. Fastened to the front 85 ends of the cables 30 by means of rings 33 are other cables 34, which are secured, by means of stirrups 35, to the front axle 25. It will be observed, particularly by reference to Fig. 2, 90 that the rear stirrups 31 are much closer to the pivot-axis of the rear axle than the front stirrups are to the pivot-axis of the front axle. Consequently if the cables are moved a differential movement of the axles will be obtained. This movement may be varied 95 by adjusting the stirrups 31 along the flange-plate 32. Cables 36, connected at their rear ends to the rings 33, slidably pass through guide-loops 37, suitably fastened to the engine, the front portions of the cables 36 be- 100 105 110

ing crossed and suitably connected to the steering-cables 8 adjacent to the front axle 7 of the engine. The front axle 25 is provided with curved tracks 38, on which rollers 39, 5 journaled in the lower ends of posts 40, run, said posts being secured to the end portions of the bolster 14. The axles 25 and 26 have journaled thereon suitable ground-wheels 41.

Supported by the bolsters 14 and 15 is a 10 water tank or reservoir 42, and located upon the same are upstanding walls 43, forming a holder for fuel, such as coal. The reservoir is surmounted by an awning or roof 44, supported on standards 45 and having suitable 15 side curtains 46. This roof is provided with a hooded extension 47, that projects beyond the front end of the tank over the links 20, thus forming a roof or cab for the engineer.

It will be observed that the device can be 20 readily attached to any ordinary traction-engine, and when so attached will properly follow the engine and remain in alinement therewith without regard to the direction of movement. This relation is maintained by

25 the rigidly-associated links 20, which links, however, permit the relative up-and-down play of the engine and tender, so as to permit their passage over uneven ground without interference. By having a four-wheeled 30 support of the character described none of the weight of the tender or the load carried thereby is brought upon the engine, and the guiding of the tender is secured by the connections between the axles and the steering-gear of the engine, the differential movement 35 of said axles effecting their proper change of direction when the front side of the engine is turned. Moreover, by having the connections as described if the guide-wheels of the 40 engine fail to direct the movement thereof—as, for instance, in soft or muddy places—the wheels of the tender will act as the guiding means.

From the foregoing it is thought that the 45 construction, operation, and many advantages of the herein-described invention will be apparent to those skilled in the art without further description, and it will be understood that various changes in the size, shape, 50 proportion, and minor details of construction may be resorted to without departing from the spirit or sacrificing any of the advantages of this invention.

Having thus described my invention, what 55 I claim as new, and desire to secure by Letters Patent, is—

1. In a traction-engine tender, the combination with a running-gear including spaced pivoted axles, of a reservoir mounted on the 60 running-gear, and means for connecting both axles to the steering-gear of a traction-engine to effect their pivotal movement.

2. In a traction-engine tender, the combination with a running-gear including spaced

pivoted axles, of a reservoir mounted on the 65 running-gear, means for connecting the tender to a traction-engine, and means for effecting a differential turning movement of said axles.

3. In a traction-engine tender, the combination with running-gear including spaced pivoted axles, of means for connecting the running-gear to a traction-engine, and means 70 connected to the axles at different distances from their pivot-axes to effect a differential 75 movement of said axles, said means being attachable to the turning-gear of a traction-engine.

4. In a traction-engine tender, the combination with running-gear including a frame and spaced axles pivoted between their ends to the frame and having walls on opposite sides of their pivot-axes, of steering devices 80 connected to both axles on opposite sides of their pivots, means for connecting said devices to the steering-gear of a traction-engine, and a reservoir mounted on the running-gear.

5. In a traction-engine tender, the combination with running-gear including spaced 90 pivoted axles, of steering-cables connected to both axles on opposite sides of their pivots and connected to each other, and means for connecting said cables to the steering-gear of a traction-engine.

6. In a traction-engine tender, the combination with running-gear including a supporting-frame and spaced axles pivoted thereto, of steering-cables connected to both axles on opposite sides of their pivots, the 100 corresponding cables of said axles being connected, and other cables for connecting said corresponding cables to the steering mechanism of a traction-engine.

7. In a traction-engine tender, the combination with running-gear including a supporting-frame and a plurality of wheeled 105 axles, of spaced draft-links pivoted to the frame and having their front ends spaced apart, and means for pivotally connecting the front spaced ends of said links to the spaced portions of a traction-engine.

8. In a traction-engine tender, the combination with running-gear including a supporting-frame having a bolster, of wheels for supporting said frame, spaced links hinged to the bolster at their rear ends, and means for pivotally connecting the front ends of the links to a traction-engine.

9. In a traction-engine tender, the combination with running-gear including a supporting-frame having a bolster, axles pivoted to the supporting-frame, wheels journaled on the axles, spaced links hinged to the bolster at their rear ends, means for pivotally connecting the front ends of the links to a traction-engine, and means for connecting the said axles to the steering-gear of said engine.

10. In a traction-engine tender, the combination with running-gear including a reach-bar, bolsters mounted transversely on said bar, and axles pivoted to the front and rear ends of the reach-bar, of wheels journalized on the axle, spaced links pivotally connected to the front bolster and having means for attachment to a traction-engine, braces connecting the links, and means attached to both axles for connecting the same to the steering-gear of such engine. 45
11. In a traction-engine tender, the combination with a reach-bar having bolsters, of a reservoir mounted on the bolsters, axles pivoted to the reach-bar, means for connecting one of the bolsters to a traction-engine, and means for connecting the axles to the steering-gear of a traction-engine. 50
12. In a traction-engine tender, the combination with a reach-bar having bolsters, of a reservoir mounted on the bolsters, axles having ball-and-socket connections, respectively, with the front and rear ends of the reach-bar, braces connecting the axles and the reach-bar, links for pivotally connecting the front bolster to a traction-engine, and cables attached to both axles and having means for connecting the same with the steering-gear of a traction-engine. 55
13. In a traction-engine tender, the combination with a wheeled running-gear, of a reservoir mounted thereon, a roof supported over the reservoir and having a hood projecting from one end, and means carried by the end having the hood for connecting the running-gear to a traction-engine. 60
14. In a traction-engine tender, the combination with a wheeled running-gear, of a reservoir mounted thereon, a roof supported over the reservoir and having a hood projecting from one end, spaced links pivotally connected to the end of the running-gear beyond which the hood extends, and means for pivotally connecting the links to a traction-engine. 65
15. In a traction-engine tender, the combination with running-gear including bolsters, of a reservoir mounted on the bolsters, a roof supported over the reservoir and projecting beyond the front end of the same, means connected to the front bolster for pivotally attaching the same to a traction-engine, axles pivoted to the running-gear, and means for connecting both axles to the steering-gear of a traction-engine. 70
16. In a traction-engine tender, the combination with running-gear comprising a reach-bar, bolsters mounted thereon, and axles pivoted therebetween, of a reservoir mounted on the bolsters, a roof supported above the reservoir, wheels journalized on the axles, links pivoted to the front bolster and having means for pivotally connecting their front ends to a traction-engine, cables connected to the axles and to each other, and other cables connected to said first-mentioned cables and arranged to be secured to the steering-gear of the traction-engine. 75
17. In a traction-engine tender, the combination with a supporting-frame, of spaced axles pivoted thereto, means for connecting the frame to a traction-engine, and means for turning the axles, said means comprising devices arranged to be connected to the steering-gear of the engine, said devices being connected to the axles and closer to the pivot-axis of one than to the other to effect a differential turning movement of said axles upon the movement of the steering-gear. 80

In testimony that I claim the foregoing as my own I have hereto affixed my signature in the presence of two witnesses.
